UNITED STATES PATENT OFFICE.

PETER O. UGARPH, OF ROCKFORD, ILLINOIS.

SAFETY-RAZOR.

1,169,892.

Specification of Letters Patent.

Patented Feb. 1, 1916.

Application filed August 2, 1915. Serial No. 43,301.

To all whom it may concern:

Be it known that I, PETER O. UGARPH, a citizen of the United States, residing at Rockford, in the county of Winnebago and 5 State of Illinois, have invented certain new and useful Improvements in Safety-Razors, of which the following is a specification.

This invention relates to safety razors and contemplates, primarily, the provision 10 of a safety razor which shall be of simple and improved construction.

Another object of my invention is to provide a safety razor in which a cap or backing, a blade and a guard are so mounted on 15 a handle as to be adjustable thereon as a unit to different angular positions relative thereto for the purpose of changing the cutting angle of the blade with respect to the longitudinal axis of the handle. In other 20 words, I provide a razor in which the operator may adjust the blade-holding means and handle relatively, so that preferring, or being accustomed to hold the handle of a razor in a certain position to obtain a certain 25 cutting angle of the blade, he may, in order to hold the razor as he desires, adjust the razor so as to obtain the desired cutting angle of the blade.

A further object is to provide a safety 30 razor having means for detachably securing a back, a blade and a guard to a handle, which will permit the blade to be quickly and easily inserted and removed from the blade-holding means.

35 My invention and its mode and principle of operation will become better understood by reference to the following description when considered in connection with the accompanying drawing, wherein—

40 Figure 1 is a side elevation of a safety razor embodying my improvements; Fig. 2 is a view, looking at the left hand side of the razor, as shown in Fig. 1; Fig. 3 is a cross-sectional view through the razor taken 45 on the line 3—3 of Fig. 2; Fig. 4 is an enlarged cross-sectional view through the cap or backing; and Fig. 5 is a perspective view of a handle provided with a different form of cam surface at its inner end from that 50 shown in Fig. 3.

Referring to the drawing, a cap or backing 6, blade 7, guard 8 and handle 9, all designated in general, comprise the main elements of my safety razor, all of which 55 will be more particularly described herein-after.

The cap or backing 6, having a slightly concave blade-receiving face 11, is provided with arcuate ends 12 projecting at right angles from the said blade-receiving face. 60 The double edged, flat blade 8, the ends of which are shaped in conformity to the ends 12, is adapted to be positioned on the backing so that its marginal portions immediately adjacent to its cutting edge rest on edge 65 portions 13 of the backing. The guard 8, the body of which is flat, the opposite longitudinal edges curved and shaped to form toothed guards, and the ends curved to conform to the inner sides of the backing ends 70 12, rests on the blade and is adapted to be clamped to the backing by means described hereinafter, so as to fixedly secure the blade in operative position. It will be here noted that the blade is held flat so as not to 75 be arched or bent, and consequently weakened at its central portion; that no members or parts project through the blade, backing, or guard for the purpose of locking these members together; and that the blade and 80 guard are held against endwise and sidewise displacement by the end portions 12 of the backing. The backing is provided at its corners with projecting guards 10 which overlie the corners of the blade and, obviously, prevent scratching or cutting while 85 in use.

The means for clamping the guard and backing together and detachably and adjustably connecting these members to the 90 handle will now be described. The handle 9 of suitable design, has secured to its inner end a cross-bar comprising a pair of diametrically oppositely extending arms 14, the outer ends of which are reduced as at 15 and 95 adapted to be pivotally mounted on the end portions 12 of the backing. For this purpose, one of the said ends 12 is provided centrally on its inner side with a circular socket 16 adapted to receive the end of one 100 of the arms 14 so as to serve as a fixed pivot, and the other end 12 is provided with a similar socket 17 and also with a slot or groove 18 leading from the socket at an incline extending away from the blade-receiving face of the backing to the edge of the said end portion, as shown clearly in Fig. 4. This groove permits the arm 14 opposite that in the fixed pivot socket 16 to be entered into socket 18 without flexing or moving 105 the arms relatively and at the same time provides a cam face 19 for drawing the outer 110

arm of the cross-head toward the guard and backing while being moved to operative position. It will be noted that the width of the groove is slightly less than the diameter 5 of the socket 17, so that a shoulder 21 is formed adjacent to the socket for precluding displacement of the adjacent end 15 from the socket.

The handle is so constructed to coöperate 10 with the guard and the sockets 16 and 18 so positioned that with a blade and guard properly mounted on the backing, when the handle has been attached to the backing, the cross-head of the handle by movement on 15 the incline groove to the socket 17 will slightly clamp the guard and blade to the blade-receiving face of the backing. This is effected by the inner end portion of the handle abutting against the guard and the 20 action of the cam face 19 in moving the cross-head inwardly toward the guard. As will be seen by reference to Fig. 3, the said inner end portion of the handle is shaped to 25 form a number of faces 22 and 23 arranged at different distances from the axis of the arms 14, the adjoining faces 23 being equidistant from said axis and a greater distance therefrom than the face 22.

When attaching the handle to the backing, 30 the handle is positioned so that its face 22 lies adjacent to the guard and its arms 14 may be easily entered on their pivots. When so assembling the razor, it will be noted that the backing will be disposed at an acute 35 angle relative to the longitudinal axis of the handle. To securely lock the handle to the backing, clamp the guard thereto, and consequently lock the blade in operative position, the handle should be turned on its 40 pivots so as to move the face 23 adjoining the face 22 into engagement with the guard, thus positioning the backing as indicated in dotted lines 24 on Fig. 1. It will be manifest 45 that by moving the several parts to different positions, the guard will have been clamped to the backing by the action of said face 23, the arms 14 flexing slightly and serving as a spring backing to permit the handle to turn beyond the high corners at 50 the juncture of the cam faces 22 and 23 and to yieldingly but firmly hold the parts in associated, operative position.

The safety razor may be used when the blade is thus positioned at right angles to 55 the longitudinal axis of the handle. Since many users prefer to have the blade positioned at an acute angle to said axis, the handle may be adjusted relatively to effect this object by moving the handle on its 60 pivots until the second face 22 engages the guard as shown in Fig. 3. Manifestly, a series of faces 23 might be provided to hold the blade positively at different cutting angles. To take up for wear between the 65 faces 23 and the guard and to secure proper

coöperation between these parts, I have provided the guard with a hardened screw 25, Fig. 3, against the head of which the faces 23 are adapted to abut. By adjusting the screw, it will be apparent that the tightening or clamping effect of the handle may be varied.

In Fig. 5, I have illustrated the handle as provided at its inner end with a slightly different cam portion. This comprises a cylindrical portion 26 concentric with the arms 14, and at its inner extremity provided with a flat surface 27 disposed in a plane at right angles to the longitudinal axis of the handle. In function the face 27 corresponds to the 80 face 22 and the periphery of the portion 26 to the faces 23. To assemble the razor, using this latter handle, the handle is attached to the guard with the parts in the position indicated by 24 (Fig. 1), that is, 85 so that the face 27 lies adjacent to the guard, permitting the arms of the handle to be entered on their pivots. It will be manifest that by turning the handle on its pivots in either direction, the guard and the blade 90 will be clamped to the backing and the handle held securely in connection therewith. Also it will be apparent that the backing, blade and guard may be adjusted as a unit about the pivot axis of a handle to 95 any angular position desired, and that either of the cutting edges of the razor may be employed, since the blade-holding means may be adjusted to operative positions on either side of the face 27.

It is believed that the foregoing will convey a clear understanding of my invention, and it should be understood that changes in detail of construction might be made without departing from the spirit and scope of the invention as expressed in the appended 100 claims.

I claim:

1. A safety razor comprising a backing having upturned ends provided with aligned 110 sockets one of said ends being also provided with a slot extending transversely of the back and communicating with the socket in said end, a blade and a guard adapted to fit said backing and be disposed between said 115 ends, a handle provided at one end with a cross-bar constructed for attachment to said backing by inserting one end in one of said sockets and entering the other end into the other socket through said slot, and means 120 on said cross-bar for clamping the guard and blade to the back upon swinging movement of the handle about the longitudinal axis of said cross bar.

2. A safety razor, comprising a backing 125 provided with raised end portions, a blade and a guard mounted on the backing between said end portions, a handle provided at one end with a cross-head, one of said raised ends being formed on its inner side 130

with a recess and the other with a recess and a cam groove leading thereto, whereby the ends of the cross-head may be entered into the said recess to effect pivotal attachment of the handle to the blade-holding means, and cam means coöoperative between the handle and blade-holding means for holding the latter in any of several different angular positions with respect to the handle,

the said cam groove being so arranged as to 10 cause the said cam means to slightly clamp the guard and blade to the backing when attaching the handle, final clamping of the several parts being effected by the said cam means when the blade-holding means and 15 handle are adjusted relatively.

PETER O. UGARPH.
